UNITED STATES PATENT OFFICE.

WALLACE L. NEWELL, OF SEATTLE, WASHINGTON.

CARGO-HANDLING DEVICE.

1,257,732.

Specification of Letters Patent. Patented Feb. 26, 1918.

Application filed March 29, 1916. Serial No. 87,614.

To all whom it may concern:

Be it known that I, WALLACE L. NEWELL, a citizen of the United States, and resident of the city of Seattle, county of King, State 5 of Washington, have invented certain new and useful Improvements in Cargo - Handling Devices, of which the following is a specification.

My invention relates to a machine or apparatus, for handling cargo between vessels and docks, and particularly cargo of the sort which is known as package freight, that is articles which are put up in packages, and which are generally handled upon trucks.

10 The object of my invention is to produce a type of apparatus which may be used to hoist cargo out of a vessel, and place it upon the trucking floor of the warehouse, and conversely to transfer such cargo from the warehouse to the hold of a vessel.

15 My invention comprises the various elements and combinations thereof, which will be hereinafter described, and then particularly pointed out in the claims.

20 In the accompanying drawings I have shown my invention in a simple type of construction, the same being illustrative of the principles of my invention, and the preferred manner of carrying out the same.

25 Figure 1 is a side elevation of my device, showing it in its relation to both the warehouse and the vessel.

Fig. 2 is top or plan view of the same.

30 Fig. 3 is an elevation and end view of the boom, and the elevated guideways.

Fig. 4 is a plan view showing the arrangement of the trucking floor in the boom.

35 Fig. 5 is an edge view of a portion of the trucking floor, showing the manner of adjusting the same to compensate for varying distances to the elevator.

40 Fig. 6 is a section showing one type of construction of the telescopic or adjustable elevator guideways.

45 Fig. 7 is a detail, showing the manner of vertically adjusting the tower and the boom.

In the drawings 9 represents a warehouse which is set back a sufficient distance from the edge of the dock to provide space for the 50 tower of my device, and 90 represents a vessel which is lying alongside of the dock.

The tower 1 is mounted upon wheels 10, which travel upon rails carried by the dock, so that the device as a whole may be traversed along the edge of the dock.

55 A boom 2, preferably of truss construction, is hinged to the tower at 11, to swing

in a vertical plane. The swinging of the boom may be done by any suitable means. As herein shown the boom is supported and controlled in its swinging movements by means of hoisting cables 12, which pass over pulleys 13, mounted respectively at the outer end of the boom, and at the upper end of the tower. This hoisting cable is controlled 60 from the power plant, which is located at 14 in the base of the tower. When not in use, the boom is intended to be swung upward to such a position as not to obstruct the movement of a vessel alongside the dock. 65

The boom 2 has a trucking floor thereon, the same being preferably provided with an adjustable section or sections, which may be moved or adjusted so as to be out of the way of the elevator guideways when the 70 boom is raised, and also so as to accommodate the position of the elevator guideways lengthwise of the boom. Such adjustment may be by the means shown in Figs. 4 and 5, in which 3 represents a section of the floor 75 which may be a fixed section, and 30 represents a section which is adjustable lengthwise of the boom, and is supported at an elevation just above the section 3, whereby it may be moved lengthwise the boom as may 80 be desired.

The adjustable section 30 is preferably provided with an inclined edge 31, so that trucks may pass from one section to the other without meeting too serious an obstruction. 90 These adjustable sections may be made in number, whatever is required to meet the necessities of the particular case. The adjustability of the floor sections may also be secured by other means.

95 The elevator guideways which in general are represented in Fig. 1 by the figure 4, of an extensible or collapsible construction as by being made telescopic in character, so that after being placed in position over the 100 hatchways, the telescopic parts thereof may be lowered into the hold of the vessel. Various means for raising and lowering these sections may be employed. I have not herein illustrated any definite means for doing this 105 as suitable means for doing this would be evident. The telescopic character of these guideways may be secured by the type of construction shown in Fig. 6. In this construction the bars 40 and their connected 110 parts, being the outermost ends of the series, are connected together and form the uppermost section, which section may or may not be adjustable vertically upon the boom. The

bars 41 and their connected parts form the next section, and the bar 42 at the center of the series, forms the lowermost section. These may be hoisted and lowered to remove 5 the guideways from the hatchways, or to lower them therein. Any other suitable type of construction than that shown, may be used as a substitute therefor.

The elevator guideways are preferably 10 mounted so that they may be adjusted lengthwise of the boom. This may be secured by various means. As herein shown, I employ a car 5, which is mounted upon a trackway 50 carried by the boom, thus permitting 15 a limited movement of the car lengthwise the boom. To prevent over-travel of the car in either direction, I may turn the ends of the rails upward to form hooks 51, at each end thereof. The position 20 of the car upon the trackway may be determined by means of the endless cable 52, which is connected with each end of the car, and extends to a controlling mechanism located at, and forming a part of the power 25 plant 14.

The elevator guideways are also preferably carried upon the car 5 by means of a hinge or pivot 53. In raising and lowering the boom, the elevator guideways may thus 30 be permitted to swing, whereby they will at all times maintain a vertical position. Such position is indicated by the broken line position shown in Fig. 1. The position of the elevator guideways when lowered, is shown 35 by full lines in Fig. 1. In the same figure by dotted lines at 43, is shown the positions of the various sections of the elevator guideways raised, or telescoped together. The number of telescopic sections may be varied 40 to suit the conditions. The various sections of the elevator guideways are preferably provided with means whereby they may be 45 steadied from the hatchways and vessel, as for instance by means of bars 45, which are adapted to engage the hatchway combings.

Mounted upon the elevator guideways are 50 platform elevators, preferably two in number, counterbalanced so that one is going up when the other is going down. In Fig. 3 55 one of these is shown at the top, and the other at the bottom, these being connected by ropes 60 which pass over pulleys, carried at the upper end thereof. These cables preferably are conducted over suitable pulleys 60 to the power plant 14 and thence back.

The control position from which the operator handles the elevators, is preferably located at the outer end of the boom, as for instance at the point 20, as in this position 65 he is able to see down the hatchways, and see all along the boom in the warehouse.

I have herein shown the tower as composed of a base section 15, and an upper or main section 16, the latter being the section 65 to which the boom is secured, and which

also carries the power plant. These two sections may be made vertically adjustable, whereby the boom may be adjusted to accommodate to delivery floors at somewhat different elevations.

The manner of raising and lowering the upper section 16 of the tower, may vary. The means herein shown consists of threaded 70 bars 17, which are connected by means of horizontal shafts 18 and bevel gears 19, so that all of them may be operated alike and simultaneously.

In operating my device the tower is moved along its trackway upon the dock to the point where it registers with the opening in 80 the warehouse, through which the freight is to pass, and also into registry with the hatchway of the vessel. The boom 2 is then lowered until it is over the hatchway. If necessary the car 5 carrying the elevator 85 guideways is moved along the boom until the guideways are directly over the hatchway. The guideway sections are then lowered until the lowermost reaches the lowermost deck, from which it is desired to take, 90 or to which it is desired to deliver freight. The elevator controlling cables are then adjusted in length to reach the desired decks.

The device is then operated by placing the freight upon the elevators and hoisting or 95 lowering the same, as may be necessary to remove the cargo from the vessel, or to place it in the vessel.

The cargo is preferably handled by means 100 of trucks, which may be lowered within the hold of the vessel when cargo is being moved from the vessel, then rolled upon the elevator platforms and hoisted to the trucking floor of the boom, at which point they are run off of the elevator platforms and transferred 105 to the warehouse.

When freight is to be placed from the warehouse into the vessel, the order of procedure is reversed, the trucks being loaded in the warehouse, run out upon the boom 110 and aboard the platform of an elevator, loaded into the vessel, and then removed to the point in the hold where the freight is being stored.

When in use, the space between the floor 115 of the boom and the floor of the warehouse is bridged by a short section of flooring, or suitable gang-way 21.

What I claim as my invention is:

1. A stevedoring machine comprising a 120 boom, means for extending the boom over the deck of a vessel, elevator guides composed of telescopic sections carried by the outer part of this boom and platform elevators running upon said guides.

2. A stevedoring machine comprising a boom adapted to be projected over the deck of a vessel and withdrawn therefrom, a plurality of sets of telescopic elevator guides carried by and adjustable lengthwise of the 130

outer part of said boom to bring them in line with the hatchways and platform elevators running upon said guides.

3. A stevedoring machine comprising a boom, means for extending the boom over the deck of a vessel and withdrawing it therefrom, elevator guides composed of telescopic sections carried by the outer part of this boom in position to register with the 10 hatchways, transverse bars carried by said guides adapted to engage the vessel to steady the guides, and platform elevators running upon said guides.

4. A stevedoring machine comprising a boom, means for supporting and handling said boom to project it over the deck of a vessel, said boom carrying a trucking floor, telescopic elevator guides carried by the outer part of this boom in position to be lowered 20 into the hatchways, and platform elevators running upon said guides.

5. A stevedoring machine comprising a boom, means for supporting and handling said boom to project it over the deck of a vessel, said boom carrying a trucking floor having adjustable sections, telescopic elevator guides carried by the outer part of this boom in position to be lowered into the 25 hatchways, and platform elevators running upon said guides.

6. A stevedoring machine comprising a hinged boom adapted to be lowered over a vessel, elevator guide ways composed of telescopic sections of which the uppermost is 35 hingedly carried by the outer end of the boom to be lowered into the hatchways, and platform elevators operable on said guide ways.

7. A stevedoring machine comprising a hinged boom adapted to be lowered over a vessel, and carrying a trucking floor containing 40 a movable section at its outer end, telescopic elevator guide ways, a hinged support for one section of said guide ways carried by the outer end of the boom, and having guiding supports thereon permitting their being lowered into the hatchways, and platform elevators operable on said guide ways.

8. A stevedoring machine comprising a 45 tower mounted for traversing along the edge of a dock, a boom hinged to the tower and adapted to be lowered over a vessel's hatchways, elevator guideways carried by the outer parts of said boom and having a guiding support thereon permitting their being lowered into the hatchways, platform elevators traveling on said guideways, and means for adjusting said guideways, lengthwise the boom.

9. A stevedoring machine comprising a 50 tower mounted for traversing along the edge of a dock, a boom hinged to the tower and adapted to be lowered over a vessel's

hatchways, a trucking floor carried by said boom and having an adjustable outer section, 65 elevator guideways carried by the outer parts of said boom and having a guiding support thereon permitting their being lowered into the hatchways, and platform elevators traveling on said guideways. 70

10. A stevedoring machine comprising a tower mounted for traversing along the edge of a dock, a boom hinged to the tower and adapted to be lowered over a vessel's hatchways, elevator guideways carried by 75 the outer parts of said boom in position to be lowered into the hatchways, means for adjusting said guideways lengthwise the boom, a trucking floor carried by the boom and containing an adjustable section, and platform elevators traveling on said guideways. 80

11. A stevedoring machine comprising a tower mounted for traversing along the edge of a dock, a boom hinged thereon and adapted to be lowered over a vessel's hatchways, 85 a trucking floor carried by the boom and containing adjustable sections, a carriage mounted for movement lengthwise the boom, elevator guide ways hingedly supported from said carriage, means permitting lowering of said elevator guideways with respect to the boom, and platform elevators mounted to travel on these guideways. 90

12. A stevedoring machine comprising a tower mounted for traversing along the edge 95 of a dock, a boom hinged thereon and adapted to be lowered over a vessel's hatchways, a trucking floor carried by the boom and containing adjustable sections, a trackway on the boom having a wheel stop at its inner 100 end, a carriage upon said trackway, telescopic elevator guideways having one section hinged upon said carriage, and elevators movable on said guideways.

13. A stevedoring machine comprising a 105 tower mounted for traversing along the edge of a dock, a boom hinged thereon and adapted to be lowered over a vessel's hatchways, a trucking floor carried by the boom and containing adjustable sections, a trackway on 110 the boom having a wheel stop at its inner end, a carriage upon said trackway, telescopic elevator guideways having one section hinged upon said carriage, and elevators movable on said guideways, and steadyng 115 means carried by the elevator guideways and adapted to engage the hatchways.

14. A stevedoring machine having a boom adapted to be extended over a vessel, extensible elevator guides carried by the outer 120 part of this boom and adapted to be entered within the hatchways of a vessel, and elevator platforms running on said guideways.

Signed at Seattle, Washington, this 24th day of March, 1916.

WALLACE L. NEWELL.
